(57) **CLAIM**

The ornamental design for a baby burp cloth, as shown and described.

DESCRIPTION

FIG. 1 is a front elevational view of a baby burp cloth, showing my new design;

FIG. 2 is a rear elevational view thereof;

FIG. 3 is top plan view thereof;

FIG. 4 is a bottom plan view thereof;

FIG. 5 is a left side elevational view thereof; and,

FIG. 6 is a right side elevational view thereof.

The dashed lines shown in the drawings represent a stitching line.
